UNITED STATES PATENT OFFICE.

OSCAR KATZENBERGER, OF CHICAGO, ILLINOIS.

LAVATORY-STRIKE.

1,131,384.

Specification of Letters Patent.

Patented Mar. 9, 1915.

Application filed July 18, 1914. Serial No. 351,748.

To all whom it may concern:

Be it known that I, OSCAR KATZENBERGER, a citizen of the United States, and a resident of Chicago, in the county of Cook and State 5 of Illinois; have invented a new and Improved Lavatory-Strike, of which the following is a full, clear, and exact description.

This invention relates to improvements in what are known as strikes, and particularly 10 to lavatory strikes, and has for an object to provide an improved structure which may be readily applied to marble slabs or other supports of various thicknesses without in-juring the slab or support, or the strike.

15 Another object of the invention is to pro-vide a strike with an adjustable plate inter-locking with the bumper carrying portion of the strike whereby the entire structure may be firmly clamped to a slab of marble or 20 other support.

In the accompanying drawings—Figure 1 is a side view of an embodiment of the in-vention, the same being shown applied; Fig. 2 is an edge view of the structure shown, 25 in Fig. 1; Fig. 3 is a section through Fig. 1 approximately on line 4—4; Fig. 4 is a sec-tional view through Fig. 3 approximately on line 4—4; Fig. 5 is a detailed fragmentary 30 sectional view through one of the plates shown in Fig. 3, the same being taken on line 5—5 of Fig. 3; Fig. 6 is a sectional view taken through one of the plates, the same being taken on line 6—6 of Fig. 3.

Referring to the accompanying drawings 35 by numerals, 1 indicates a marble slab or other support and 2 a door. Arranged ad-jacent the marble slab 1 is a clamping plate 3 formed with ears or enlargements 4 and 5, which ears or enlargements are formed with 40 slots or notches 6 and 7 which accommodate the locking flanges 8 and 9 arranged on the face plate 10, which face plate is part of the side plate 11. The face plate 10 as shown in Fig. 3 is wider than the slab 1 so that slabs 45 of various thicknesses may be used, or rather the strike is adapted for slabs of various thicknesses without necessitating any chance of injury to the slab or to the strike. In case the slab 1 was thicker than shown in Fig. 3 the clamping plate 3 would merely be moved farther toward the edge 12. Con-nected with the face plate 10 is a bumper re-ceiving socket member 13 which may be held in place by any suitable means, as for in- 50 stance projections 14 extending through the face plate 10, which projections are upset

or riveted as shown in Fig. 3. The socket member 13 is designed to receive a bumper 15 of any desired material, as for instance rubber, so as to not only stop the movement 60 of door 2 but cushion the closing thereof. It is to be noted that the various parts of the strike are formed from pressed material, and that the face plate 10 is merely an ex-tension of the side plate 11. It will also be 65 noted that face plate 10 has the sides thereof bent up for forming the flanges 8 and 9 and the end bent up for forming the end member 12 which acts as a stop or limiting member for the clamping plate 3. It will be ob- 70 served that the flanges 8 and 9 fall short of the plate 11 as shown in Fig. 3 whereby the clamping plate 3 may be threaded over the flanges 8 and 9 before the device is applied.

In Fig. 6 it will be observed that the por-tions 4 and 5 may be easily fitted into notches 16 and 17 after which the clamping plate may be slid properly over the flanges 8 and 9. After the plates have been ar-ranged as shown in Fig. 3 a bolt 18 is passed 80 through a suitable hole provided in the slab 1 and through the apertures provided in the plates 3 and 11. Upon tightening up the nuts of the bolt the strike is ready for use.

What I claim is—

1. In a strike of the character described, a pair of plates, one of said plates acting as a front plate and the other as a clamping plate, a face plate extending from said front plate, said face plate being formed with di-verging flanges, said clamping plate being 90 formed with diverging slots designed to ac-commodate said flanges, means for holding a bumper on said face plate, and means for clamping said clamping plate and said front 95 plate to a support.

2. In a strike of the character described, a pair of clamping plates adapted to fit on opposite sides of a support, a clamping bolt for clamping said plates to said support, one 100 of said clamping plates being formed with a face plate extending substantially at right angles to the body of the plate, said face plate being formed with a pair of diverging flanges, which extend across the face plate 105 to a position adjacent the body of said last mentioned clamping plate, the other of said clamping plates being formed with slots for receiving said flanges, whereby said face plate is held in proper position, the arrange- 110 ment of said flanges falling short of the body of the first mentioned clamping plate

allowing the ready application of said second mentioned clamping plate before the plates are arranged on said support, and means for holding a bumper on said face plate.

3. In a supporting fixture of the character described, a pair of plates, one of said plates acting as a front plate and the other as a clamping plate, and a face plate extending from said front plate, said face plate having

obliquely arranged flanges, said clamping plate being formed with slots designed to accommodate said flanges.

In testimony whereof I have signed my name to this specification in the presence of 15 two subscribing witnesses.

OSCAR KATZENBERGER.
